UNITED STATES PATENT OFFICE.

MURRAY GRAFF, OF NEW YORK, N. Y.

LINED HAT AND HAT LINING.

Application filed March 14, 1922, Serial No. 543,733. Renewed December 17, 1923.

To all whom it may concern:

Be it known that I, MURRAY GRAFF, citizen of the United States, and resident of New York city, in the county of Bronx and State of New York, have invented certain new and useful Improvements in Lined Hats and Hat Linings, of which the following is a specification.

This invention relates to improvements in lined hats and hat linings. Its objects are to produce, at a low manufacturing cost, lined soft hats having creased crowns on which the lining crown piece may be bent and clamped to hold the upper portion of the lining properly in place; to produce the hat linings in such a manner that a lining of a given size for a hat of a given size will properly fit a hat crown of another size, whereby it will not be required, as according to present practice, to make a given size of hat lining for each given size of hat crown, and, at the same time, to make the linings of a more pleasing appearance than they have been heretofore made; to make the linings of a larger circumference than they have been heretofore made adjacent and immediately below the crown piece, in order that the linings may not, at their upper portion adjacent the crown piece, unduly bear on coiffures at the top of the head, as is the case with hat linings as heretofore manufactured; to obviate the use of a buckram crown piece and a covering for it by making the crown piece preferably of a single ply of flexible fabric maintainable in either a flat condition or in a bowed and clamping condition, as may be required, by providing the lining at its crown piece portion with a light-weight, metallic and preferably laterally bendable distender.

It is not necessary, however, in accordance with this invention, that the distender should be laterally bendable because where it is not desired to use the distender as a clamp for holding the top of the lining to a soft hat crown crease-wall, the distender may be made of sufficiently stiff material to resist such lateral bending and to be used flatwise in men's hats and women's hats having stiff crowns.

In general practice, the one ply fabric crown piece will be a woven or printed label of flexible material; but the invention is not limited, of course, to crown piece-forming labels.

Heretofore, the crown pieces have comprised an oval buckram stiffening piece which, if bent sharply, becomes more or less permanently deformed either in the factory or in the course of shipment or otherwise; and this piece of buckram has been by commercial custom required to be concealed by an under covering piece of material.

This practice involves not only the use of two pieces of material for making the crown piece, but also the labor and expense of dieing out and handling two crown piece forming plies instead of one.

In large quantity production the prior practice is substantially more expensive than is the practice of the present invention.

In the accompanying drawings forming a part hereof and illustrating the invention in the best form now known to me,

Fig. 1 is a side elevation of the out or wrong side of my new hat lining detached.

Fig. 2 is a top plan view of what is shown in Fig. 1.

Fig. 3 is an enlarged vertical view of a portion of the vertical side of the side piece to show the preferably triangularly fluted ribs and interspaces of the lining.

Fig. 4 is a top plan view of a portion of the lining as viewed from the upper end of it while it is in an approximately tubular state before it is attached to the crown piece.

Fig. 5 is an end plan view of a portion of the lining as viewed from the under end of it while it is in an approximately tubular state before it is attached to the crown piece.

Fig. 6 shows the wire distending ring for the top of the lining.

Fig. 7 is an enlarged detail at line 7—7 of Fig. 2 and shows the assemblage of the distending ring with the crown piece and side piece.

Fig. 8 is a top plan view of a soft hat having a creased-in crown top.

Fig. 9 is a section at line 9—9 of Fig. 8 and shows the interior of the hat provided with my new lining and its distending ring and crown piece bent upwardly into clamping engagement with the crown crease-wall of the hat.

Fig. 10 is an enlarged view showing a cross-section of a continuous oval trough formed around the upper side of the crown piece which forms the under trough wall and the superposed, stitched-together mar-

gin of the crown piece and side piece which are turned over the upper side of the crown piece to form the upper flange of the trough for reception of the lining distender.

5 In the illustrated form of the invention, the oval crown piece 1 is shown as a woven label of one ply, but it need not be a label, and if desired might be made of a plurality of plies. The margin of the crown piece is 10 stitched at 2 in an oval seam to the margin of the side piece 1^a, the margin of the side piece being superposed on that margin of the crown piece surface which forms its under side when the lining is in place in a 15 hat. The raw edge of the crown piece and the thereto adjacent raw edge of the side piece are preferably flush. As the seaming operation at 2 progresses, the superposed stitched together margins are turned over in 20 flange forming fashion so as to over-hang the upper side of the crown piece; that is, to over-hang the side which is opposed to the hat crown when the lining is in place in a hat, whereby a continuous oval trough 4 is 25 formed around the wrong or upper side of the crown piece. The inturned, two-ply flange thus formed is indicated by 5.

An endless crown piece distender in the form of an oval wire ring 6 is sprung into 30 the trough and keeps the crown piece initially and also permanently flat, unless it is to be used as a hat crown crease clamp. In its function as a crown piece distender for holding the crown piece flat, it also keeps the 35 upper, adjacent margin of the side piece distended, and thus operates as a distender for the upper closed end of the cup-like lining.

The side piece is fluted or plaited in upwardly and downwardly alternating rib and 40 groove-like space style from the crown piece downwardly, to a greater or lesser extent as may be desired. It is shown so fluted down to its under edge which is shown below the upper edge of the sweat leather 7 in the 45 soft hat crown 8 shown with an inbent crease wall 9. Preferably, for the best results, the fluting ribs 10 are widest at their upper ends where they are sewn to the crown piece and taper gradually downwardly so 50 that when viewed in plan they are approximately of elongated, triangular shape. They are made preferably about $\frac{3}{16}$ of an inch wide at their upper ends and about $\frac{1}{16}$ of an inch wide at their under ends. The groove-like 55 spaces between the ribs are indicated by 11. As the side piece is of relatively light weight fabric, the precise form of the alternating ribs and grooves is not necessarily fully maintained at all times, but, nevertheless, the 60 goods having been once fluted, as stated, retain substantially the alternating rib and groove structure. Where the upper and wider ends of the ribs are sewn to the crown piece, the side piece is gathered at intervals 65 as at 12 in order to make the goods come out

even, as the phrase is in sewing parlance, and also in order to give the side piece a new and useful cross-sectional fullness and projection outwardly of the crown piece at, near and downwardly below its under side. 70 The fluting ribs actually stiffen the lining material and promote the circumferentially bellying out of the lining adjacent the under side of the crown piece, whereby the cup shaped lining thus enlarged at its upper end 75 better fits coiffures on the top of women's heads than has been the case heretofore where the upper portion of the cup-like lining has been of substantially lesser dimension in cross-section than is now the case. 80

It is to be understood that the side pieces may be fluted in the up and down direction with parallel alternating ribs and groove-like spaces, and the results obtainable from such a style of fluting are very good; but 85 in practice I find that the triangular form described gives somewhat and, in fact, quite pronounced, better results. Aesthetically considered, the up and down fluted linings are very desirable; but, in addition to the 90 mechanical function of causing the upper end of the lining to belly out beyond the crown piece, the ribs also function in another important and economic particular for they make the lining circumferentially 95 elastic so that an upwardly and downwardly fluted side piece, in connection with the crown piece, results in a lining which, although made of a definite normal cross-sectional size, is practically and commercially 100 100

useful for lining hats of somewhat larger sizes or even of somewhat smaller sizes. By present practice, hat linings are made in various definite sizes, each given size being for a hat crown of a corresponding size. By 105 present practice the crown pieces comprise a buckram stiffener covered on the under side by a piece of material usually the same size as the side piece, both pieces being died out and involving two separate dieing operations. If the buckram becomes unduly bent the crown piece becomes objectionably deformed; and the use of the buckram and its under side cover also entails other expense 110 that is obviated by the present invention. 115

The crown piece distending ring for hats, other than soft hats having their crowns creased in, need not be laterally bendable as heretofore explained; but it is preferred to make them of bendable metal so that each 120 may be useful either for flatwise distention of the crown piece or for upward bending so as to be pinched upon the sides and clamp the crown piece to the sides of the crease-wall 9 of a soft hat for holding the crown piece of the lining on the under marginal bulge 9^a of the crease-wall, and for also maintaining the crease in shape. This is an important use of the flexible distender as a part of linings for men's soft hats. 125 130

When so used, the fluted side piece, because of its fluted structure, rises up into the spaces at each side of the crown crease and generally into contact with the hat crown wall, as indicated at 13, causing the lining generally but not invariably to remain bowed up into the position as shown. This is due to the resistance of the flatwise upwardly and downwardly curvature of the 10 ribs at 13. The fluted ribs give a certain degree of inherent stiffness to the side piece when the ribs are bent as indicated. In metal, this function would be recognized as an engineering fact, and it is quite a practical reality even in connection with relatively light weight silks, or other fabrics commonly used for hat linings. The usual slanted side seam of the side piece is indicated by 14, the side piece being shown 20 cut as usual on the bias. It will be observed that the trough in which the distender is mounted is formed by a single sewing operation, which is an economic feature. The ring-like distender is invisible 25 from the interior of the hat lining, and by my invention the so called draw-string type of hat lining of the earlier art; the so called ornate seam, involving the use of uncovered cord exposed between the crown piece and 30 side piece, is obviated; and so also is obviated the so called welt lining between the crown and side piece as involved in the prior art. The metal distender ring has a considerable degree of inherent stiffness and 35 functions to stretch out the lining adjacent the seam by which the crown piece and the side piece are united together; and it also functions to resist buckling of the crown piece, which is made preferably of a freely 40 flexible fabric instead of buckram which has a considerable inherent stiffness and often becomes more or less bent or crumpled to the commercial injury of the hat linings. The area of the crown piece is considerably 45 less than the cross-sectional area of the distended side piece, and smaller, in relation thereto, than in all prior practice known to me.

The metal distender ring is endless so 50 that it has no free ends to work out of place and pierce the goods. In the enlarged Fig. 10, the seam 2 is shown spaced apart from the edges of the crown piece and side piece to a greater extent than occurs in the actual size of the commercial product. In Figs. 7 and 10, the side piece is shown plain, without any fluting, and in the broader aspect of the invention, the side piece may 55 be of plain non-fluted goods, if preferred. 60 Another feature of the invention lies in the use of the endless wire distender as a frame for keeping the label, whether woven or printed, in a taut condition, thereby adding to the neatness and commercial advantage of 65 the hat lining. The woven label art and the

printed fabric label art each has its own peculiar conditions; and such labels have raw or cut edges to some extent. By framing crown piece forming labels, as herein shown, the raw or cut edges require no special treatment like the well known bending over on the label backs of the raw or cut edge margins of such labels and hot-creasing them in special machines. In the present case, such edges and margins form merely 70 the concealed edges around the upper or wrong outside of the tip portion adjacent the hat crown. The distending ring fits tightly in the trough-like pocket provided for it, and is peripherally hugged by the side wall of the trough or pocket. It is not necessary that the crown piece be oval or that the distending ring be oval, and, of course, a metal distending ring having ends 75 and of a suitable form might be used in a pocket formed otherwise than as a trough. 80 If desired, the distending ring may be omitted in order to obtain a uniformly soft lining without any stiffening members at all. And whether the side piece be in any-wise fluted or be made of plain smooth goods, the side piece, being of and by itself by usual practice a tube of uniform diameter, the gathering of the upper margin of the side piece at 12 in order to make the upper end of the attached tube forming side piece fit the margin of the crown piece, causes the upper portion of the side piece to belly outwardly around, adjacent and below the crown piece. Such soft linings are 90 desirable for some classes and styles of hats; and in the form of the invention shown, the lining is in its entirety a soft, freely flexible lining without any stiffening members at 95 all, but by preference has the open sided, flanged trough or pocket described, into and out of which the distending ring may be moved when desired, the distending ring being preferably demountable and replaceable at will. 100

The margin of the crown piece or tip 1 is bent over that side of the crown piece which in use is its top side and is herein shown as its wrong side to form a continuous flange *a* that overhangs the main portion of the crown piece, as shown in Fig. 10. Thus the crown piece is formed around the edge of its normally flat main portion with a pocket wall *b*, and this pocket wall projects laterally outwards beyond the seam or stitching at 2, whereby the margins of the crown piece and side piece are superposedly united. The endless crown piece distender or metallic ring 6 is placed in this pocket and tightly fits therein, whereby the pocket wall *b* of the crown piece and the main body of the crown piece are laterally distended and the distender ring itself is compressively held in place in the pocket, the peripheral surface 115 of the distender ring being located in the 120

4
lateral bottom of the pocket and outwardly of the seam 2. The conjoint result of the pocket so formed and of the so dimensioned ring with the side piece 1^a vertically fluted with folds which are widest at the top adjacent the crown piece and taper gradually downwards, is to cause the so fluted side piece to belly outwards around and slightly below the crown piece, whereby the upper 10 end of the hat lining is substantially enlarged, better to fit protuberant coiffures. The metal distending ring is difficultly deformable by pressure on its periphery, but is transversely bendable.

15 What I claim is:

1. As a new article of manufacture, a hat lining comprising a seamed-together crown piece and side piece and a metal distending ring; the crown piece being formed with a 20 bent flange-like pocket side forming, marginal wall overhanging and spaced apart from the normally top side of its main portion, and with a lateral pocket wall outwardly of the seam which unites the crown 25 piece and side piece; thereby forming a pocket in which the distending ring is snugly located with its periphery outwardly of said seam.

2. As a new article of manufacture, a hat 30 lining comprising a seamed-together crown piece and side piece and a transversely bendable metal distending ring; the crown piece being formed with a bent flange-like pocket side forming, marginal wall overhanging and spaced apart from the normally top side of its main portion, and with a lateral pocket wall outwardly of the seam which unites the 35 crown piece and side piece; thereby forming a pocket in which the distending ring is snugly located with its periphery outwardly of said seam.

3. As a new article of manufacture, a hat 40 lining comprising a seamed-together crown piece and side piece and a metal distending ring; the crown piece being formed with a 45 bent flange-like pocket side forming, marginal wall overhanging and spaced apart from the normally top side of its main portion,

and with a lateral pocket wall outwardly of the seam which unites the crown piece and 50 side piece; thereby forming a pocket in which the distending ring is snugly located with its periphery outwardly of said seam; and the side lining being fluted from its upper end downwardly with fluting ribs 55 widest at their upper ends adjacent the crown piece and tapering gradually downwards.

4. As a new article of manufacture, a hat having a soft, creased-in crown and a lining 60 comprising a seamed-together crown piece and side piece and a transversely bendable metal distending ring; the crown piece being formed with a bent flange-like pocket side forming, marginal wall overhanging and spaced apart from the normally top side of its main portion, and with a lateral pocket wall outwardly of the seam which unites the crown piece and side piece; thereby forming a pocket in which the distending 65 ring is snugly located with its periphery outwardly of said seam; the transversely bendable metal distending ring being bent upwardly to clamp the top of the lining on the creased-in crown.

5. As a new article of manufacture, a hat lining comprising a seamed-together crown piece and side piece and a metal distending ring; the crown piece being formed with a 70 bent flange-like pocket side forming, marginal wall overhanging and spaced apart from the normally top side of its main portion, and with a lateral pocket wall outwardly of the seam which unites the crown piece and side piece; thereby forming a 75 pocket in which the distending ring is snugly located with its periphery outwardly of said seam; the distending ring being unconfined around its inner circumferential wall and being thereby demountable and re- 80 placeable at will.

Signed at New York city, in the county of New York and State of New York, this 28 day of February, A. D. 1922.

MURRAY GRAFF.
